UNITED STATES PATENT OFFICE

WILLIAM H. BRIDGES, OF GRAND RAPIDS, MICHIGAN.

TOILET-BRUSH.

1,141,662.

Specification of Letters Patent. Patented June 1, 1915.

Application filed June 8, 1914. Serial No. 843,776.

To all whom it may concern:

Be it known that I, WILLIAM H. BRIDGES, a citizen of the United States, residing at Grand Rapids, in the county of Kent and State of Michigan, have invented certain new and useful Improvements in Toilet-Brushes, of which the following is a specification.

My invention relates to improvements in toilet brushes, and its objects are: First, to provide a brush of which the bristles may be readily folded down to form a very thin brush to carry in the pocket. Second, to provide a brush that may be readily assembled or taken apart for renewing the bristles, and, third, to provide a means whereby the bristles may be locked firmly in any desired position. I attain these objects by the mechanism illustrated in the accompanying drawing, in which—

Figure 1 is a longitudinal section of the brush handle with the bristles in normal position for brushing clothes, &c. Fig. 2 is a longitudinal section of the frame 25 with the bristles folded down inside the frame and one form of inclosing case shown thereon in longitudinal section. Fig. 3 is a transverse section of the frame with the bristles in normal position. Fig. 4 is a 30 plan of the bristle holder detached from the frame and with no bristles connected therewith. Fig. 5 is an end view of the bristle holder showing gear teeth by means of which the holder is actuated to adjust 35 the bristles as desired. Fig. 6 is a plan of the actuating plate by means of which the bristle holders are adjusted. Fig. 7 is a longitudinal section of the frame showing 40 indentures in the side for the reception of the pintles on the ends of the bristle holders. Fig. 8 is a plan of a short piece of the back of the body of the brush showing how the bristle holders may be locked in the desired 45 positions. Fig. 9 is a transverse section of the brush frame showing a modified form of case for protecting the brush when folded together for carrying in the pocket. Fig. 10 is a transverse section of the case shown in Fig. 2.

Similar letters refer to similar parts throughout the several views.

The frame 1 of this brush should be made of aluminum, or other light sheet metal that may be readily stamped into the desired form, and the sides should be provided with a series of small holes, or depressions,

as *e e*, (preferably small conical depressions) to receive the conical pintles 8 8 on the ends of the bristle holders 2. This form of frame will be slightly springy so that the bristle 60 holders may be readily slid into, or out of place in the handle, as desired, and may be readily made to oscillate for the purpose of carrying the bristles to the position desired.

The bristles 4 are secured in the bristle 65 holders 2 in the usual manner of securing them in an ordinary brush back, the only difference being that each cross, or transverse line of bristles is mounted independent of all other transverse lines, and each is 70 arranged to be adjusted independent of the others.

While there are many ways in which the bristle holders may be mounted for convenient adjustment, I have found that the most 75 convenient and available means is to make two or three gear teeth, 3, on each bristle holder, and as there is not sufficient space between the bristle holders to permit of using full gear wheels I find it necessary, or 80 at least advantageous to make these teeth integral with, and on one side only, of the holders, as indicated in Fig. 5, and I actuate the holders by means of a slide 5 which is mounted in the frame 1 directly back of 85 the teeth 3 on the holders. This slide is provided with a series of openings, 9, in which the teeth 3 travel as the slide is moved longitudinally for actuating the holders. This slide is manipulated by means of a handle 7, 90 that is securely attached to, or made integral with the slide, and which passes out through a slot, 6, in the back of the frame 1 in position to be readily accessible to the operator.

When assembling these brushes the slide 5 95 is placed upon the inner surface of the back of the frame 1 with the handle 7 projecting out through the slot 6, when the several bristle holders 2 are sprung in place in the frame in normal, or projected position, as in Fig. 1, with one of the gear teeth 3 passing through its adjacent opening 9 in the slide 5, until all the bristle holders are in position and the brush is in condition for use. I provide for locking the slide in place to 100 hold the bristles in the desired positions, by means of a latch 12 that is pivotally secured, or hinged to the back as at *c*. This latch has an opening *f* through it in position to interlock with the handle 7 when the slide is in 110 the position indicated in Figs. 2 and 8, and is made of a proper length so it will leave

the end of the slot 6 open sufficiently to allow the handle 7 to pass through between it and the end of the slot when the slide is in the position indicated in Fig. 1.

5 When the bristles 4 of this brush are swung down in the positions shown in Fig. 2 the entire brush may be slid into a case or box 10, as indicated in Fig. 2, so that the bristles are entirely covered and protected from dust, insects, &c. In Fig. 9 the brush frame 1 forms one half of the box or case that is designed to protect the bristles 4, the cover 11 being provided with inwardly curved sides *a* that engage the outwardly curved 15 sides *b* of the brush frame so that the cover may be slid upon the frame longitudinally and will protect the bristles as completely as if the case 10 were used, with the advantage of using less material, consequently less 20 weight, less labor to make, and much less expense for dies &c. for making the form shown in Fig. 9.

What I claim as new, and desire to secure by Letters Patent of the United States, is:

25 In a toilet brush, a channeled frame, revoluble bristle holders pivotally mounted in said frame, bristles mounted on said holders, gear teeth formed on one side of said holders; a slide having openings to receive said teeth, slidably mounted in the frame, said frame having a slot through the back, a handle on the slide projecting through said slot, a latch pivotally mounted on the back of the frame in position to be 30 made to engage the handle and lock the slide in desired positions.

Signed at Grand Rapids, Michigan, June 5th, 1914.

WILLIAM H. BRIDGES.

In presence of—

GRACE DE VORE,
I. J. CILLEY.
